UNITED STATES PATENT OFFICE.

AUGUST NELSON, OF MINNEAPOLIS, MINNESOTA.

MOP.

1,268,271.

Specification of Letters Patent. Patented June 4, 1918.

Application filed January 25, 1917. Serial No. 144,348.

To all whom it may concern:

Be it known that I, AUGUST NELSON, a citizen of the United States, residing at Minneapolis, in the county of Hennepin and 5 State of Minnesota, have invented certain new and useful Improvements in Mops; and I do hereby declare the following to be a full, clear, and exact description of the invention, such as will enable others skilled 10 in the art to which it appertains to make and use the same.

My invention has for its object to provide an improved mop for cleaning floors, the same having a cylinder and piston attachment for discharging water onto the floor or for taking up the water from the floor, at will. The term "mop" is used in a broad sense. The mop, as constructed, however, preferably includes a scrubbing brush, as 20 well as a scraper blade.

The preferred form of the improved mop is illustrated in the accompanying drawings wherein like characters indicate like parts throughout the several views. Referring to 25 the drawings:

Figure 1 is a plan view of the improved mop;

Fig. 2 is a section on the line 2—2 of Fig. 1;

Fig. 3 is an enlarged section on the same line as Fig. 2, but showing only the lower portion of the mop structure; and

Fig. 4 is a side elevation of the parts shown in Fig. 3.

The mop head is hollow and preferably in the form of a cylindrical tube 5 having, at its central portion an internally-threaded cap 6 with an axial port 7. This cap 6 is preferably screwed onto the lower end of a 40 pump cylinder 8, which at its rear end, has a head 9 formed with a long projecting stem 10 that affords a convenient handle for the mop.

Working within the cylinder 8 is a piston 45 11 having a long rod 12 that projects through the tubular stem 10, so that its outer end may be engaged by one of the hands of the operator, while his other hand grips the tubular stem of handle 10.

On the longitudinal line of its outer portion, the mop head 5 is formed with water ports 13. The ends of the said head 5, of course, are closed.

The numeral 14 indicates a heavy but 55 flexible rubber scraper blade, the upper edge of which is attached to the tube of the mop

head 5; and the numeral 15 indicates an auxiliary scraper blade, preferably of raw hide, or leather. The upper edges of the scraper blades 14 and 15 are connected together and fastened to the top of the mop head 5 by suitable screws 16. The said blades 14 and 15 respectively, are formed with water ports 17 and 18, the latter of which are of much greater diameter than 60 the former. These ports 17 and 18 are so located, in respect to each other and in respect to the water ports 13 of the mop head that when the blades are forced against the head and onto the floor, as shown in Fig. 4, 70 all of the said ports 13, 17 and 18 will be in registration, so that water may be discharged from or down into the said mop head, at will.

The numeral 19 indicates a scrubbing 75 brush which, as shown is rigidly, but detachably secured to the mop head 5, by means of screws 20.

The preferred manner of using this mop is as follows:

While the piston 11 is lowered in the cylinder, the mop head may be dipped into clean water or suds water contained in a pail, or other receptacle, and this water may be drawn into the cylinder by pulling 85 the piston outward. Then the water may be sprayed onto the floor where desired while the mop is raised, simply by giving the piston a downward movement in the cylinder, the water, of course, being discharged through the ports 13, 17 and 18.

Then by the use of the brush 20, the floor may be scrubbed and then, by using the blade 14 as a scraper, as shown in Fig. 3, while drawing the mop rearward, the water 95 on any particular part of the floor may be collected. The water may then be drawn back into the cylinder by giving the piston an outward movement in the cylinder while the mop is being forced forward in the position shown in Fig. 4. When the mop is forced forward, as shown in Fig. 4, the water forced ahead of the scraper, will run to the relatively larger ports 18, and by the latter, will be directed to the ports 17 and 100

thence to the ports 13, so that the water will be rapidly collected and drawn into the cylinder. This dirty water may then be ejected into a catch pail or other receptacle, simply by giving the piston another downward 110 movement of the cylinder.

With this improved mop, the best kind of

scrubbing can be rapidly done without requiring the operator, at any time, to get upon his knees, and moreover, both the clean and dirty water can be handled without requiring the operator to put his hands in the water. Moreover, mopping can be done without producing splashing of walls or casements. The efficiency of the device has been demonstrated in actual practice.

10. What I claim is:

1. In a mop, the combination with a cylinder and piston working therein, of a mop head connected to the head end of the cylinder and having a water port, and a scraper blade attached to the mop head and having a water port, said scraper blade arranged to draw away from the mop head during the movement thereof in one direction and to fold thereunder during a reverse movement of said mop head, said two water ports, when the scraper blade is folded under the mop head, being in registration, the one with the other.

2. In a mop, the combination with a cylinder and piston working therein, of a mop head connected to the head end of the cylinder and having transverse water ports, a flexible scraper blade adapted to be folded onto the mop head and having its upper edge attached thereto, and water ports in the scraper blade and arranged to register with the water ports in the mop head when the scraper blade is folded thereon.

3. In a mop, the combination with a cylinder and piston working therein, of a mop head connected to the head end of said cylinder and having transverse water ports, a scraper blade attached to said head and having water ports adapted to register with the water ports of said mop head, the said cylinder having a projecting tubular stem affording a handle, and said piston having a rod projecting through said tubular stem, so that its outer end may be engaged to operate said piston.

4. In a mop, the combination with a cyl-

inder and a piston working therein, said cylinder having a tubular stem affording a handle and said piston having a rod extending through said stem so that it may be engaged to operate said piston, a tubular 50 mop head intermediately attached to the head end of said cylinder and in communication with the interior thereof, said head having transversely spaced water ports, a rubber scraper blade attached to the top 55 of said mop head at its upper edge and having water ports adapted to register with the water ports of said mop head.

5. In a mop, the combination with a cylinder and a piston working therein, said 60 cylinder having a tubular stem affording a handle and said piston having a rod extending through said stem so that it may be engaged to operate said piston, a tubular 65 mop head intermediately attached to the head end of said cylinder and in communication with the interior thereof, said head having transversely spaced water ports, a rubber scraper blade attached to the top of 70 said mop head at its upper edge and having water ports adapted to register with the water ports of said mop head, and a flexible auxiliary scraper blade attached at its upper edge to the upper edge of the main scraper blade, terminating in its lower edge short of 75 the lower edge of said main blade, and having relatively large water ports that register with the water ports of said main blade, whereby, water collected by said two scraper 80 blades may be drawn into the cylinder, said two scraper blades adapted to fold, the one upon the other and upon the tubular mop head.

In testimony whereof I affix my signature in presence of two witnesses.

AUGUST NELSON.
